FERDINAND FOGELSTRAND, OF NEW HAVEN, CONNECTICUT, ASSIGNOR TO
SARGENT & CO., OF SAME PLACE.

Design No. 4,473, dated November 15, 1870.

DESIGN FOR A THUMB-LATCH.

The Schedule referred to in these Letters Patent and making part of the same

To all whom it may concern:

Be it known that I, FERDINAND FOGELSTRAND, of New Haven, in the county of New Haven and State of Connecticut, have invented a new Design for Thumb-Latch; and I do hereby declare the following, when taken in connection with the accompanying illustrations, to be a full, clear, and exact description of the same, and which said illustrations constitute part of this specification, and represent in—

Figure 1, a front view of the handle;

Figure 2, a front view of the plate; and in

Figure 3, a front view of the lever.

This invention relates to a design for thumb-latch, and consists in the peculiar configuration of the parts as hereafter described and shown in the accompanying illustrations.

Each of the parts has a plain edge, giving to the surface a paneled appearance, the ground of which is matted and ornamented by tracery raised to the same level with the edge, all as fully shown in the accompanying illustrations.

While the parts are intended all to be used together, they may be used separately. I, therefore, do not wish to confine myself to the combination of the three pieces; but

I claim as my invention—

The design for thumb-latch, as herein described and shown in the accompanying illustrations.

FERDINAND FOGELSTRAND.
